UNITED STATES PATENT OFFICE

GILBERT R. LIVINGSTON, OF SANTA MONICA, CALIFORNIA

DESIGN FOR A GAME BOARD

Application filed November 24, 1931. Serial No. 41,835. Term of patent 3½ years.

To all whom it may concern:

Be it known that I, GILBERT R. LIVINGSTON, a citizen of the United States, residing at Santa Monica, in the county of Los Angeles and State of California, have invented a new, original, and ornamental Design for Game Boards, of which the following is a specification, reference being had to the accompanying drawings, forming part thereof.

I claim:

The ornamental design for a game board, as shown.

GILBERT R. LIVINGSTON.
